UNITED STATES PATENT OFFICE.

PARKER T. SIMMONS, OF ATTLEBORO FALLS, MASSACHUSETTS.

BASE-BALL-GAME APPARATUS.

1,153,719.

Specification of Letters Patent. Patented Sept. 14, 1915.

Application filed May 22, 1914. Serial No. 840,275.

To all whom it may concern:

Be it known that I, PARKER T. SIMMONS, a citizen of the United States, residing at Attleboro Falls, in the county of Bristol and State of Massachusetts, have invented new and useful Improvements in Base-Ball-Game Apparatus, of which the following is a specification.

The invention relates to parlor base ball games of the type in which a board is provided having a diamond and field depicted thereon, and including a device for pitching a small ball and another for batting it, and it is a particular object to improve the construction of the pitching and batting devices. It is sought to simplify the mounting and other structural details of the pitching and catching devices.

A further important object is to provide an improved pitching device, particularly with regard to its accuracy.

It is a valuable attainment of the invention that the pitching device may be adjusted to deliver a ball at any pre-determined elevation and its direction varied, at will, within a certain limit.

Additional objects and advantages will appear, some of which will be apparent in the construction, arrangement and combination of parts herein described, and illustrated in the drawings, in which,

Figure 1 is a plan view of a game constructed in accordance with my invention. Fig. 2 is a side elevation of the pitcher, in detail. Fig. 3 is a front view thereof. Fig. 4 is a detail of the batter. Fig. 5 is a detail of the batter mounting. Fig. 6 is a detail of the back stop. Fig. 7 is a detail of one of the field cups. Fig. 8 is a longitudinal sectional view.

There is illustrated a rectangular game board 10 having at each corner a removable pin 11, set vertically on the board, a strip of cloth 12 being stretched around these pins 45 to form a fence. At a proper point adjacent one end of the board a base ball diamond 13 is printed or otherwise indicated, having the usual bases indicated thereon. Adjacent the first base and a little to the left there is a catching device 14, comprising a strip of sheet metal having partly conical form secured upon the board with its large end presented toward the home plate 15. A little

to the right of the second and third bases similar stops 16 and 17 are attached. A 55 similar one 16' is also located a little to the left of the second base. The latter is designated as the "short-stop" while the first three mentioned represent the respective base-men, and may be so designated in a 60 suitable manner. In the approximate positions ordinarily occupied by the fielders, the stops 18, 19, and 20 are located in the field A, being similar to, but slightly larger than, the one 14 above described. 65

A pitcher device 21 is mounted centrally of the diamond, and a batting device 22 is mounted adjacent the home plate 15, including a bat 23 having a radius of action including the home plate. The pitching de-

vice is constructed and adapted as will be more particularly described, to throw a ball 24 over the home plate or close beside it, and immediately behind the home plate there is provided a large stop device 25 corre- 75

sponding to the catcher, by which the ball will be caught when projected along certain lines. Located so as to be between two straight lines projected from a medial point in the radius of action of the bat past the 80

stop 18 at respective sides, there is a cup 26 located adjacent the end of the board farthest from the diamond. Cups 27 and 28 are located on the board in a similar relation to the stops 19 and 20. Located a little 85

nearer the diamond cups 29 and 30 are fixed in the field intermediately of the field stops 18, 19, and 20. The cups 26 to 30 inclusive are each stamped integrally from sheet metal and have a projecting lip or flange 31 90

set in the face of the board 10, a suitable opening being bored in the board to receive the cup proper. If desired, the cups may be open at the bottom, for the passage of the ball therethrough, and openings 32 may be 95 formed centrally of all of the stops, leading through the board to a space 33 formed thereunder and having an inclined floor 34 by which the balls are led under action of gravity to one side of the device. 100

The pitcher device comprises a plate 35 including a foot-piece 36 secured upon the upper side of the board, and an integral vertical portion 37 approximately aligned with the home plate, being also located centrally of the diamond 13. This vertical

portion of the plate includes a central semi-circular lobe 39 having a concentric opening therein, a grip portion 40 at what may be termed the rear end of the plate, and a 5 spring anchorage lug 41 at the forward end. The plate as described may be stamped integrally from sheet metal. A suitable pintle 42 is engaged through the aperture of the lobe 39, having an enlarged head 43 at one 10 end, between which and the lobe 38 the enlarged end 44 of a pitching arm 45 is revolvably mounted, being suitably apertured for the purpose. At the outer end of this arm there is formed a suitable cup 46, 15 adapted to receive and loosely hold the ball 24 when in set position. In this position, the arm extends rearwardly at a slight inclination, and has connected thereto at an intermediate point a spring 47 attached to 20 the anchorage 41 under tension tending to throw the arm forcibly forward. For holding the arm in set position, a cam portion 48 is formed thereon rearwardly of the arm, its maximum radius being adjacent the arm, 25 where a notch 49 is formed, adapted to receive the bill 50 of a trigger 51 pivoted adjacent the lower part of the lobe 39, and having a finger piece 52 extending rearwardly beside the grip portion 40, before 30 mentioned. At its forward side the enlarged end of the arm 45 is provided with an extension 53, having a curved forward edge 54, and mounted revolvably on the vertical portion of the plate in the path of this extension there is a cam 55, by which the limit of 35 the stroke of the arm may be fixed. This cam may be simply clamped releasably to the plate, or may be mounted upon a revolvable key 56, so that a player may vary the 40 direction of the ball at will by turning the key. Also, the direction of the ball may be varied laterally by slightly flexing the vertical portion of the plate, the resiliency of the metal permitting this without becoming 45 deformed within the necessary limits. It will be possible to accomplish this flexure at the same time that the trigger is operated, without difficulty, the finger piece 52 being operable by the thumb, lateral pressure of 50 which will at the same time flex the plate in one direction, while the fore-finger may be used to flex the plate in the opposite direction simultaneously with the operation of the trigger. 55 The batting device comprises a standard 57 formed of crimped sheet metal, the lower end being slightly stretched at the sides and extended in a horizontal foot-piece 58 secured by screws to the surface of the board 60 10. The foot-piece is provided with a central aperture 59, in which there is set one end of a helical spring 60 coiled around the standard 57, the upper end being disposed against the rear side of a bat member 61 65 formed of a planiform plate of sheet metal

having its inner end 62 curved around the standard 57. The upper end of the standard 57 is flanged to prevent casual removal of the bat.

Owing to the general familiarity with 70 games of this character, it will be unnecessary to explain how it may be played, except to say that the bat is to be operated preferably by the pressure of the left thumb of one player while the pitching device is operated by another player. The bat is formed with a rounded outer end against which the thumb may be pressed. The force of the blow of the bat may be governed by moving it in a reverse direction one or more turns, 75 and when released the spring 60 completely spends itself.

The cup 26 being most likely of the three outermost ones to be entered by the ball, is given a value of a two-base hit, the central 85 one 27 being the most difficult of entry is given a value of a "home run", while the cup 28 is given a value of a three-base hit. The cups 29 and 30 having a comparatively clear passage from the bat are called "outs", 90 putting the bats-man out of play, when he bats a ball thereinto. It is important to note that the value of the introduction of the ball into the cups 26, 27, and 28 is nearly proportional to the difficulty of getting a ball 95 into these locations, it being impossible for a ball to roll direct from the bat to these cups. It will be obvious that some change in the construction of certain details of my invention will be possible without departing from the spirit of the invention. 100

The specific construction of the bat and pitcher mounting enables the production of these parts and their assembly at a very low cost, and at the same time they represent 105 highly efficient devices.

In practice, it has been found possible to produce this device in a large size with eminently satisfactory results, and it also operates well when constructed in smaller 110 sizes. Thus, the board has, in some cases, been made three by six feet in plan, and also about half this size.

What is claimed:

1. In an apparatus of the class described, 115 a pitcher device comprising a horizontal foot plate, an integral resilient upstanding plate thereon, an arm having an enlarged base pivoted on the upstanding plate and provided with a ball receiving cup at the outer 120 end, a spring anchored upon the plate and engaging the arm for movement thereof in one direction, the enlargement of the arm having a cam portion at its rear side terminating in a notch at its major radius, a 125 trigger device pivoted on the plate and having a bill to engage the notch and an integral grip portion on the upstanding plate adapted to be grasped with the trigger, as described.

2. In a pitching device a support, an oscillating arm carried thereby, means for oscillating the arm, the arm having a stop portion, a cam device mounted revolubly on the support in the path of the stop portion of the arm, and means to adjust the cam.

In testimony whereof I have hereunto set

my hand in presence of two subscribing witnesses.

PARKER T. SIMMONS.
